UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE.

1,251,872.

Specification of Letters Patent. Patented Jan. 1, 1918.

Application filed July 22, 1914. Serial No. 852,345.

To all whom it may concern:

Be it known that I, ALBERT H. DE VOE, a citizen of the United States, residing at Westfield, in the county of Union and State 5 of New Jersey, have invented certain new and useful Improvements in Sewing-Machines, of which the following is a specification, reference being had therein to the accompanying drawings.

10 This invention has for its primary object to provide a sewing machine for stitching lengthwise of hollow or tubular objects or portions of garments in such manner that the body of the object may pass freely beneath and longitudinally of the work-support without obstruction while the seam is 15 stitched upon the upper face of the work-support, thereby permitting the stitching to be produced by a single handling of the garment as in ordinary straightaway stitching operations. It has for its further object a 20 construction and arrangement of mechanism appropriate to the particular form of frame designed to accomplish the primary object.

25 According to the present improvement, in its preferred embodiment, the frame is constructed with a hollow standard from the upper end of which extends a lateral arm comprising an arched tubular intermediate 30 member and connected at its free end with the upper side of a lateral work-supporting member having a free space around the opposite sides, the bottom and both ends. The work-supporting member is disposed transversely to both the standard, from which it is laterally offset, and the intermediate member.

35 The work-supporting member is composed of a rigid portion and two laterally and reciprocally swinging sections each provided near its free end with a transverse loop-taker shaft upon each of which is preferably mounted a rotary hook having a thread-cavity to receive a thread-case which 45 is held in position therein and restrained against rotation by means of a pivotally mounted holder or hanger sustained by its respective swinging section of the work-supporting member. The loop-takers are 50 arranged upon the adjacent sides of the swinging sections, and are readily accessible by swinging the sections outwardly from their normal positions, in which they are adapted to be locked adjustably toward and 55 from each other by suitable means.

Coöoperating with the loop-takers are two

needles mounted within a removable clamp upon a vibratory needle-arm which is fulcrumed upon a fixed part of the work-supporting member adjacent the intermediate 60 member and is actuated by a connection with the main-shaft extending through the upper portion of the standard and said intermediate member. The loop-taker shafts are preferably connected by means of pairs of 65 spiral gears with intermediate shafts journaled within and longitudinally of the respective work-support sections and each connected independently of the other with the main-shaft by means of an apertured belt 70 and pin-pulleys of well known construction.

75 The work is advanced to the stitching mechanism at the free end of the work-supporting member by means of a feed-dog and connections with the main-shaft extending through the hollow intermediate frame member and lengthwise of the work-support member; and the presser-foot is preferably carried by a swinging arm fixed upon a rock-shaft journaled upon the intermediate frame 80 member and embraced by the pressure spring whose normal action is counteracted in raising the presser-foot by means of a manually actuated lifting lever fulcrumed upon the standard and engaging a depending arm of 85 the presser-foot rock-shaft. The machine is preferably provided with a rotary take-up fixed upon the end of the main-shaft adjacent the work-receiving end of the work-supporting member and acting in conjunction 90 with suitable tension devices and thread-guiding elements in the handling of the thread in its passage to the needles.

95 In the accompanying drawings, Figures 1 and 2 are perspective views of the operative parts of a machine constructed in accordance with the present improvement, and with the frame represented in dotted lines, and Fig. 3 is a perspective view of the feeding mechanism detached from the machine. 100 Fig. 4 is a plan view, upon a larger scale, of the work-supporting member with the throat-plate omitted. Fig. 5 is a sectional elevation of the same. Figs. 6 and 7 are end views of the work-supporting member, 105 the frame being partly in section, and Fig. 8 is a transverse section of the same intermediate its ends. Fig. 9 is a perspective view of the thread-case of one of the loop-takers with its holder. Fig. 10 is a perspective view showing the inner face of one of the latch-plates. Fig. 11 is a plan and Fig. 12

a side elevation of the frame of the machine.

As represented in the drawings, the frame comprises the hollow upright standard 1 having the flanged base 2 and sustaining at its upper end the lateral arm comprising the arched tubular member 3 and the horizontally extending work-supporting member 4 depending therefrom. The intermediate frame member is provided in its outer end with an enlargement 3' affording a cavity which merges into a cavity 4' below the same at the adjacent end of the work-supporting member. The work-supporting member is cut away upon opposite sides intermediate its upper and lower faces to form lateral longitudinally extending recesses housing the lateral swinging sections 5 and 6 having at their rearward extremities respectively the tongue 7 and forked lug 8 apertured to embrace the fulcrum-stud 9 extending from the bottom of the cavity 4'.

The member 4 is formed with a transverse recess 10 near its forward end to afford a loop-taker cavity intermediate the adjacent portions of the sections 5 and 6, thereby providing a post 11 at the forward or delivery extremity of the member 4 and rising from the bottom flange or plate 4'' which affords a support for the laterally swinging sections 5 and 6.

The throat-plate 12 is secured upon the post 11 at its forward end by means of the screw 13, and upon the upper face of the rigid member 4 at its rearward end by means of the screws 14. The throat-plate is provided with the usual feed-dog apertures 15 and with the needle apertures 16 intermediate the same.

40 The outer portions of the swinging work-support sections 5 and 6 are extended upwardly with their upper faces flush with those of the rigid portion of the member 4, and are provided with inwardly extending 45 stud-shafts 17 secured in position by set-screws 18 and having eccentric bearing portions 19 adjacent their heads upon which are journaled the spirally-toothed hub portions 20 of the cup-shaped loop-taking elements 50 21 each formed with the loop-seizing beak 22 and provided with an axial thread-cavity in the inner face adjacent the other loop-taking element, as represented more particularly in Fig. 6. Mounted within and longitudinally of each of the work-support sections 5 and 6 is a longitudinally extending loop-taker shaft 23 journaled at opposite ends in the bearing bushings 24 and having fixed thereon the spirally toothed pinion 25 60 meshing with the similar teeth of the loop-taker hub 20.

The loop-taker actuating shafts 23 have secured upon their rearward ends the pin-pulleys 26 surrounded by the apertured flexible belts 27 and 28 which embrace respec-

tively the larger pin-pulleys 29 and 30 fixed upon the short cross-shaft 31 which is suitably mounted within the cavity 3' of the frame member 3. The shaft 31 has fixed thereon intermediate the pin-pulleys 29 and 30 the spiral-gear 32 meshing with a similar gear 33 fixed upon the main-shaft 34 which extends across the upper end of the standard 1 and through the frame member 3 in which it is suitably journaled, bearing bosses 35 and 36 being provided therefor. The main-shaft is provided upon the end adjacent the bearing boss 35 with the hand-wheel 37.

Mounted upon the transverse fulcrum-pin 38, sustained in the frame member 4 adjacent the member 3, is the hub 39 of the vibratory needle-carrying lever 40 which is provided in its outer end with the apertured boss 41 in which is secured the shank of the needle-clamp 42 provided with the reciprocating needles 43 cooperating with the loop-taking elements 21 in the production of stitches. Secured within a suitably apertured boss of the hub 39 is the rearwardly extending pin 44 to which is fitted the transverse socket 45 of the strap 46 embracing the actuating eccentric 47 fixed upon the main-shaft 34. The needle-arm 40 thus derives operative vibratory movements from the eccentric 47 and imparts to the needles 43 their reciprocatory movements.

As represented in the drawings, the loop-takers are of well known construction. Each of the loop-taking elements 21 is provided in the lateral walls of its thread-cavity with an annular bearing shoulder to which is fitted, as represented in Fig. 6, the peripheral bearing rib 48 of a thread-case 49 containing a bobbin provided with a mass of lower thread. At its inner end and at the upper side, each thread-case is formed with the spaced lugs 50 affording segmental shoulders which are received by the rounded upper edge of the holding plate or hanger 51 which is provided with a finger 52 entering the space between said lugs for restraining the thread-case against rotation with its respective loop-taking element. The holding plate 51 has at its lower extremity an angular block 53 which is forked to embrace the lug 54 projecting inwardly from the swinging work-support section to which it is pivotally connected by means of the pin 55.

The holder-plate 51, which normally supports the thread-case within its loop-taking element, is provided with a lateral arm 56 which is engaged by the spring-catch 57 adapted to lock the same in operative position, the holder-plate being swung backwardly, when its respective swinging work-support section is retracted (as represented in dotted lines in Fig. 4) for removal of the thread-case and replacement of the lower-thread bobbin.

The post 11 is shown provided upon its outer face with a rectangular projection 11' upon opposite sides of which are adjustably secured by means of the fastening screws 58 entering suitable elongated apertures therein in the latch-plates 59 which are notched in their adjacent edges to embrace said projection. The latch-plates are provided in their inner faces and at their adjacent edges with recesses 59' to afford adjacent their opposite edges abrupt shoulders, and the post 11 is formed in its outer face with a recess 11'' in register with the recesses 59'. The latch-plates 59 are provided with threaded apertures extending parallel with their outer faces in which are inserted adjusting screws 60 whose points are adapted to bear upon the extension 11' of the post 11 for adjusting the positions of said latch-plates and correspondingly positioning the catch-shoulders afforded by the recesses 59' and the outer edges of said plates, the fastening screws 58 being temporarily loosened for the purpose.

Each of the swinging work-support sections is formed in its outer end with a transverse slot in which is pivotally mounted by means of the pin 61 a catch-lever 62 formed with a hooked nose 63 at its outer end and flattened adjacent its respective pivotal pin 61 to receive the free end of a flat spring 64 secured to a suitable seat in the outer edge of the section by means of a screw 65. The extremities of the sections 5 and 6 are provided with apertures 66 embracing portions of the catch-levers 62 and affording access thereto for pressure by the finger of the operator for retracting the catch-levers. When the swinging sections 5 are in operative position, their inner edges are held in contact with the adjacent edges of the catch-plate 59 by engagement of the catch-levers 62 with the shoulders of the recesses 59', and either of them may be readily moved into inoperative position for access to its respective loop-taker by retraction of the spring-pressed catch-lever 62.

The feed-dog 67 is shown provided with the usual serrated feeding surfaces, and has a cylindrical shank 68 which is fitted within the tubular arm 69 of a rock-lever having the transversely apertured lug 70 and the rearwardly extending arm 71, said rock-lever working in a central channel 4''' arranged in the upper portion of the work-supporting member 4. The apertured lug 70 of the rock-lever is entered by and supported upon the transverse fulcrum-pin 72 mounted in the member 4 intermediate its ends. The rock-lever arm 71 carries at its rearward extremity the screw-stud 73 which is embraced by the apertured boss 74 at the lower end of a link 75 whose apertured opposite end embraces a stud-screw 76 tapped into the apertured boss of the needle-lever hub 39. Rocking movements are thus imparted to the

lever-arm 69 from the vibratory needle-lever for communicating to the feed-dog its rising and falling movements.

The shank 68 of the feed-dog is of tubular form terminating at the end adjacent the same in a socket in which is rigidly secured by means of the set-screw 77 one end of a thin resilient rod 78 whose opposite end is secured by means of screws 79 in a socket formed in the head 80 of a rocking pin 81. The pin 81 is journaled within a transverse boss 82 formed at the end of a depending arm 83 of a rocking frame constituting the feed-rocker and formed with the sleeves 84 and 85 journaled upon the main-shaft 34 and connected together by means of the yoke 86 bridging the intermeshing gears 32 and 33.

The sleeve 85 of the rocking frame has secured upon its extremity the split hub 87 of an upwardly extending arm 88 carrying a stud 89 which is embraced by one apertured extremity of the link 90 whose forked and apertured opposite extremity is pivotally connected by means of the pin 91 with the upper end of a vibratory bar 92 adjustably secured near its lower end by means of the set-screw 93 within the apertured head 94 of a rocking fulcrum-pin 95 journaled within and transversely of the standard 1. The bar 92 is slidably fitted near its upper end within the transverse boss 96 of a strap or sleeve 97 embracing the feed eccentric 98 which is mounted for lateral adjustment upon the slide-plate 99 of the collar 100 fixed upon the main-shaft, the adjustable eccentric being of well known form.

By loosening the set-screw 93, the bar 92 may be adjusted vertically relatively to its fulcrum-pin 95, and the position of the connecting link 90 may be changed to correspondingly vary the point of connection between the arm 88 of the feed-rocker and the actuating eccentric 98. As will be observed, the feed-rocker communicates its operative movements to the feed-dog through the arm 83 and rod 78 in the production of the work-advancing movements, the slight bending of the rod 78 intermediate its ends being permitted by reason of the clearance therefor afforded by the tubular form of the feed-dog shank 68.

The frame member 3 has upon the side thereof toward which the work-supporting member 4 extends the bearing lugs 101 in which is mounted the rock-shaft 102 to the end of which above the work-supporting member is secured by means of the set-screw 103 the hub 104 of the arm 105 overhanging the member 4 and provided at its extremity with the vertically apertured boss 106. Within the boss 106 is secured by means of the set-screw 107 the presser-bar 108 having pivotally secured to its lower end by means

of the pin 109 the rocking presser-foot 110 opposed to the feed-dog 67.

Surrounding the rock-shaft 102 is a coil-spring 111 having one end secured to the 5 adjacent bearing boss 101 and the other end secured to a collar 112 fastened upon the rock-shaft by means of the set-screw 113, this spring acting through the rock-shaft and arm 105 to force the presser-foot to- 10 ward the throat-plate and feed-dog. The rock-shaft 102 has a depending arm 114 adapted for engagement by a lateral stud 115 carried by one arm 116 of an elbow-lever mounted upon the fulcrum-pin 117 jour- 15 naled in the standard 1 and provided with the lateral arm 118 connected with the treadle-rod 119. By drawing down the rod 119 the shaft 102 may be rocked in opposition to its spring 111 to lift the presser- 20 foot.

The frame member 3 is provided above its connection with the member 4 with a boss 120 upon which are secured the needle-thread tension devices 121 with an inter- 25 posed guide-plate 122 provided with suitably disposed guide-eyes for directing the threads to and from the tension, the delivery eyes 123 being disposed above the space intermediate the component disks 124 of a ro- 30 tary tension-wheel of well known construction fixed upon the adjacent extremity of the main-shaft 34. In practice, the needle-threads are led through their respective tension devices and delivered to the take-up 35 through the guide-eyes 123 and are thence led through the fixed guide-eye 125 to the needles.

The main-shaft 34 has secured thereon within the standard 1 the toothed pinion 126 40 meshing with the gear-wheel 127 which is mounted upon the short shaft 128 journaled within and transversely of the standard 1 and having the attached grooved belt-wheel 129 embraced by the driving belt 130. Power 45 is thus communicated to the main-shaft by means housed entirely within the hollow standard and from which the operator is effectively shielded. The position of the main-shaft 34 substantially at right angles with 50 the work-support, at the end of which the operator sits in operating the machine, makes it practicable to apply the hand-wheel 37 at the end of the main-shaft beyond the frame standard where it is conveniently accessible to the operator.

In the installation of the machine, the base of the standard is preferably bolted upon the work-table near the edge at which the operator sits, the frame member 3 being 60 disposed parallel with and the member 4 directed away from such edge of the table. In the closing of the tubular portions of garments, the garments are carried over the table and beneath the junction of the 65 frame members 3 and 4, the marginal por-

tions to be united being carried up over the work-supporting member and fed to the stitch-forming mechanism and away from the operator beyond the end of the member 4 where they are deposited without necessity 70 of further handling on the part of the operator or disengagement from the machine, as in cylinder-bed machines heretofore in common use. This method of handling the work is permissible in accordance with the 75 present improvement by reason of the special form of the frame which affords a clear space beneath and at the sides and ends of the work-supporting member for free and unobstructed passage of the body of the garment, and partly by reason of the construction and arrangement of the mechanism in which the work-engaging elements are sustained and operated by means following the angular contour of the frame and which 80 present the least possible obstruction of the view of the operator to the work at and beyond the stitching point. The operator is thus enabled to inspect not only the action of the machine upon the work but to inspect 85 the finished work as it is leaving the machine to insure its freedom from defect through any fault in the action of the machine.

From the foregoing description, it will be 90 evident that a specially important feature of the present improvement is the form of the frame of which the work-supporting member is laterally offset and spaced from the standard relatively to which it extends 95 transversely materially above the base of the latter. As shown and described herein, the work-supporting member and all the operative parts of the mechanism are sustained by the standard and extend from the same side 100 thereof, thereby conforming with the shape of the frame in their construction and arrangement. The present construction therefore provides a frame in which the component parts are designed to provide an advantageous means of suspension for the work-supporting member, no additional frame member being provided to sustain operative parts, which are all housed within or sustained by the frame as described.

While the improvement is disclosed herein in its preferred form, the invention is evidently not limited to the present specific embodiment, but includes considerable variation in the form, construction and arrangement of the parts.

Having thus set forth the nature of the invention, what I claim herein is:

1. A sewing machine frame composed exclusively of an upright member or standard, 125 a lateral or intermediate member connected therewith and extending outwardly therefrom, and a work-supporting arm depending from said intermediate member and disposed transversely to both of the other mem- 130

- bers with a clear space above the plane of the base of the standard, said work supporting arm being extended away from said standard.
- 5 2. A sewing machine comprising a frame including a standard and a lateral work-supporting arm sustained by said standard and constructed with a section movable laterally of said arm, and stitch-forming mechanism incorporated in said frame and including a loop-taker carried by said section. 70
- 10 3. A sewing machine frame comprising a standard and a lateral work-supporting member sustained thereby and constructed with two reciprocally movable sections. 75
- 15 4. A sewing machine frame comprising a standard and a lateral work-supporting member formed with a rigid portion extending to its extremity more remote from the standard and two independently and reciprocally movable lateral sections normally superposed upon the rigid portion. 80
- 20 5. A sewing machine constructed with a frame comprising a standard and a lateral work-supporting member sustained thereby and constructed with a laterally movable section, a loop-taker sustained by and bodily movable with said section, and a reciprocating needle coöperating with said loop-taker. 85
- 25 6. A sewing machine constructed with a frame comprising a standard and a lateral work-supporting member sustained thereby and constructed with a laterally movable section, a loop-taker sustained by and bodily movable with said section, and a reciprocating needle sustained upon a portion of the frame fixed relatively to said laterally movable section. 90
- 30 7. A sewing machine constructed with a frame comprising a standard and a lateral work-supporting member sustained thereby and constructed with laterally and reciprocally movable sections, loop-takers each sustained by and bodily movable with one of said sections, and reciprocating needles coöperating with said loop-takers. 95
- 35 8. A sewing machine constructed with a frame comprising a standard and a lateral work-supporting member sustained thereby and constructed with laterally and reciprocally movable sections, loop-takers each sustained by and bodily movable with one of said sections, and reciprocating needles sustained for coöperation with said loop-takers upon a portion of the frame fixed relatively to said laterally movable sections. 100
- 40 9. A sewing machine constructed with a frame comprising a standard and a lateral arm including a work-supporting member offset from and extending in a direction transverse to said standard and connected therewith and disposed intermediate the top and base of the latter, and stitch-forming mechanism comprising a reciprocating needle and a loop-taker both sustained by said arm. 105
- 45 10. A sewing machine constructed with a frame comprising a standard and a lateral arm sustained in fixed relation therewith and having a work-supporting member disposed transversely to and laterally offset from said standard and a connecting member by which said work-supporting member is suspended with a clear space beneath the same from end to end above the level of the base of the standard, a shaft journaled within and transversely of the standard, stitch-forming mechanism including a reciprocating needle and a coöperating loop-taker disposed at the end of the work-supporting member farthest from the connecting member, and connections with said shaft extending through said arm for actuating both the needle and the loop-taker. 110
- 50 11. A sewing machine constructed with a frame comprising a standard and an arm including a laterally extending work-supporting member arranged out of alinement with the standard and a rigid connecting member between said standard and work-supporting member from which the latter depends, in combination with stitch-forming mechanism sustained wholly by said arm. 115
- 55 12. A sewing machine constructed with a frame comprising a standard and an arm composed of a work-supporting member disposed transversely to and laterally offset from said standard and having beneath and at the opposite ends a clear and unobstructed space, and a rigid member connected to said standard and sustaining said work-supporting member, in combination with stitch-forming mechanism sustained wholly by said arm. 120
- 60 13. A sewing machine constructed with a frame comprising a standard and an arm composed of a work-supporting member disposed transversely to and laterally offset from said standard and having beneath and at the opposite ends a clear and unobstructed space, and a rigid member connected to said standard and sustaining said work-supporting member, a shaft journaled within and transverse to the standard and longitudinally of said rigid member, a reciprocating needle, a coöperating loop-taker sustained by said work-supporting member, and driving means for said needle and loop-taker connected with said shaft and housed within said arm. 125
- 65 14. A sewing machine constructed with a frame comprising a standard and an arm composed of a work-supporting member disposed transversely to and laterally offset from said standard and having beneath and at the opposite ends a clear and unobstructed space, and a rigid member connected to said standard and sustaining said work-supporting member, a shaft journaled within and transverse to the standard and longitudinally of said rigid member, a reciprocating 130

- needle and a coöperating loop-taker sustained by said arm, and a take-up element sustained by said arm and operatively connected with said shaft.
- 5 . 15. A sewing machine constructed with a frame comprising a standard and an arm composed of a work-supporting member disposed transversely to and laterally offset from said standard and having beneath and 10 at the opposite ends a clear and unobstructed space, and a rigid member connected to said standard and sustaining said work-supporting member, a shaft journaled within and transverse to the standard and longitudinally of said rigid member, a reciprocating needle and a coöperating loop-taker sustained by said arm, and a take-up element fixed upon said shaft.
16. A sewing machine constructed with a 20 frame comprising a standard and an arm composed of a work-supporting member disposed transversely to and laterally offset from said standard and having beneath and at the opposite ends a clear and unobstructed 25 space, and a rigid member connected to said standard and sustaining said work-supporting member, a shaft journaled within and transverse to the standard and longitudinally of said rigid member, a reciprocating 30 needle and a coöperating loop-taker sustained by said arm, a feed-dog disposed within said work-supporting member, and an operative connection between the feed-dog and said shaft.
- 35 17. A sewing machine constructed with a frame comprising a standard and an arm including a laterally extending work-supporting member sustained by and arranged out of alinement with the standard, and 40 stitch-forming mechanism comprising a reciprocating needle and a coöperating loop-taker sustained by said arm.
18. A sewing machine constructed with a frame comprising a standard and a lateral 45 work-supporting member sustained thereby and constructed with a laterally movable section, a loop-taker sustained by and bodily movable with said section, and a reciprocating needle sustained upon said arm independently of said section.
- 50 19. A sewing machine constructed with a frame comprising a standard and a lateral work-supporting member sustained thereby and constructed with a laterally movable 55 section, a loop-taker sustained by and bodily movable with said section, means for securing said section adjustably in operative position, and a reciprocating needle coöperating with said loop-taker.
- 60 20. A sewing machine constructed with a frame comprising a standard and a lateral work-supporting member sustained thereby and constructed with laterally and reciprocally movable sections, loop-takers each sus- 65 tained by and bodily movable with one of said sections, means for securing said sections in operative position adjustably relatively to each other, and reciprocating needles coöperating with said loop-takers.
21. A sewing machine constructed with a frame comprising a standard and a lateral work-supporting member sustained thereby and having a laterally movable section, a main-shaft journaled in said frame, a loop-taker actuating shaft journaled within and longitudinally of said section, an operative connection between said shafts, a loop-taker mounted in said section and operatively connected with said actuating shaft, and a reciprocating needle with which said loop-taker cooperates.
22. A sewing machine constructed with a frame comprising a standard and a lateral work-supporting member sustained thereby and having laterally and reciprocally movable sections, a main-shaft journaled in said frame, loop-taker actuating shafts journaled within and longitudinally of said sections, operative connections between the main-shaft and said loop-taker actuating shafts, loop-takers each sustained by and bodily movable with one of said sections and each operatively connected with one of said actuating shafts, and reciprocating needles coöperating with said loop-takers.
23. A sewing machine constructed with a frame comprising a standard and a lateral work-supporting member sustained thereby and having laterally swinging sections, a main-shaft journaled in said frame, loop-taker actuating shafts journaled within and longitudinally of said sections, operative connections between the main-shaft and said loop-taker actuating shafts, loop-takers each sustained by and bodily movable with one of said sections and each operatively connected with one of said actuating shafts, and reciprocating needles coöperating with said loop-takers.
24. A sewing machine constructed with a frame comprising a standard and a lateral work-supporting member sustained thereby and having laterally and reciprocally movable sections, a main-shaft journaled in said frame, loop-taker actuating shafts journaled within and longitudinally of said sections, independent belt-and-pulley connections between the main-shaft and said actuating shafts, respectively, loop-takers each sustained by and bodily movable with one of said sections and each operatively connected with one of said actuating shafts, and reciprocating needles coöperating with said loop-takers.
25. A sewing machine constructed with a frame comprising a standard and a lateral work-supporting member sustained thereby and having a laterally movable section, a loop-taking element sustained by and bodily movable with said section, a thread-case

disposed within the field of action of said loop-taking element, a thread-case holder sustained by said section, and a reciprocating needle coöperating with said loop-taking element.

26. A sewing machine constructed with a frame comprising a standard and a lateral work-supporting member sustained thereby and having laterally and reciprocally movable sections, loop-taking elements each sustained by and bodily movable with one of said sections, thread-cases each disposed within the field of action of one of said loop-taking elements, thread-case holders each sustained by one of said sections adjacent its respective loop-taker, and reciprocating needles coöperating with said loop-taking elements.

27. A sewing machine constructed with a frame comprising a standard and a lateral work-supporting member sustained by, disposed transversely to and laterally offset from said standard with the lower side and the ends thereof exposed and unobstructed for free movement of tubular articles to, along and from the same, in combination with stitch-forming and feeding mechanisms each deriving operative movements from actuating means extending through the standard and its connection with the work-supporting member.

28. A sewing machine constructed with a frame comprising a standard and a lateral work-supporting member sustained by, disposed transversely to and laterally offset from said standard with the lower side and the ends thereof exposed and unobstructed for free movement of tubular articles to, along and from the same, in combination with stitch-forming mechanism comprising a reciprocating needle and a coöperating loop-taker journaled within the work-supporting member remotely from its connection with the standard, and actuating means for said needle and loop-taker both extending transversely from the standard and longitudinally of said work-supporting member.

29. In a sewing machine, in combination, a frame including a standard, and a work-supporting arm free at one end and at its opposite end joined to said standard, said arm comprising a section which is free at one end and is adapted to swing outwardly, and a loop-taker mounted in said section adjacent the free end thereof, whereby said loop-taker is adapted for bodily movement into and out of operative relation with the needle, and means for confining said support in operative position wherein the loop-taker coöperates with the needle in the production of stitches.

30. A sewing machine constructed with a frame comprising a standard and an arm having a work-supporting member disposed

transversely to and laterally offset from said standard and having beneath and at the opposite ends a clear and unobstructed space, a vibratory needle-arm mounted upon said frame and overhanging the work-supporting member and movable upon a fulcrum transverse to the latter, a needle carried by said vibratory arm, actuating means for said vibratory arm, and a loop-taker sustained by said work-supporting member and coöperating with said needle.

31. A sewing machine constructed with a frame comprising a standard and an arm including a laterally extending work-supporting member arranged out of alinement with the standard, and a connecting member between said standard and the work-supporting member from which the latter depends, a main-shaft extending across said standard and lengthwise of said connecting member, a vibratory needle-arm overhanging and extending lengthwise of the work-supporting member and movable upon a fulcrum transverse to the latter, and an operative connection between said main-shaft and the needle-arm.

32. A sewing machine constructed with a frame comprising a standard and an arm including a laterally extending work-supporting member arranged out of alinement with the standard, and a connecting member between said standard and the work-supporting member from which the latter depends, a main-shaft extending across said standard and lengthwise of said connecting member and provided adjacent the work-supporting member with an actuating eccentric, a vibratory needle-arm overhanging and extending lengthwise of the work-supporting member and movable upon a fulcrum transverse to the latter, a slide-pin rigidly connected with the needle-arm, and a strap embracing said actuating eccentric and provided with a transverse socket entered by said slide-pin.

33. A sewing machine constructed with a frame comprising a standard and an arm including a laterally extending work-supporting member arranged out of alinement with the standard, and a connecting member between said standard and the work-supporting member from which the latter depends, a rock-shaft mounted upon and disposed lengthwise of the connecting frame member, a presser-arm fixed upon said rock-shaft and overhanging and extending lengthwise of the work-supporting member, and a presser-foot sustained by said presser-arm.

34. A sewing machine constructed with a frame comprising a standard and an arm including a laterally extending work-supporting member arranged out of alinement with the standard, and a connecting member between said standard and the work-support-

ing member from which the latter depends, a rock-shaft mounted upon and disposed lengthwise of the connecting frame member, a presser-arm fixed upon said rock-shaft and overhanging and extending lengthwise of the work-supporting member, a presser-foot sustained by said presser-arm, and a coil-spring embracing said rock-shaft and adapted to force the presser-foot upon the work-supporting member.

35. A sewing machine constructed with a frame comprising a standard and an arm including a laterally extending work-supporting member arranged out of alinement with the standard, and a connecting member between said standard and the work-supporting member from which the latter depends, a rock-shaft mounted upon and disposed lengthwise of the connecting frame member, a presser-arm fixed upon said rock-shaft and overhanging and extending lengthwise of the work-supporting member, a presser-foot sustained by said presser-arm, a coil-spring embracing said rock-shaft and adapted to force the presser-foot upon the work-supporting member, an arm fixed upon said rock-shaft and extending within the frame standard, and a manually actuated rock-lever having an arm adapted for engagement with said depending arm of the rock-shaft for lifting the presser-foot in opposition to said spring.

36. A sewing machine constructed with a frame comprising a hollow standard and an arm including a laterally extending work-supporting member arranged out of alinement with the standard, and a connecting member between said standard and the work-supporting member from which the latter depends, a main-shaft extending across the standard and lengthwise of the connecting frame member, stitch-forming mechanism sustained by said work-supporting member, an operative connection adjacent the latter between said main-shaft and the stitch-forming mechanism, and a hand-wheel applied to the main-shaft at the side of said standard more remote from the work-supporting member.

50 37. A sewing machine constructed with a frame comprising a hollow standard and an arm including a laterally extending work-supporting member arranged out of alinement with the standard, and a connecting member between said standard and the work-supporting member from which the latter depends, a main-shaft extending across the standard and lengthwise of the connecting frame member, stitch-forming mechanism sustained by said work-supporting member, operative connections adjacent the latter between said main-shaft and the stitch-forming mechanism, and driving means extend-

ing upwardly through the standard from beneath the base of the latter and operatively connected with the main-shaft.

38. A sewing machine constructed with a frame comprising a hollow standard and a lateral work-supporting arm sustained thereby, a main-shaft journaled in said frame and extending transversely across said standard, stitch-forming mechanism sustained by said work-supporting arm, operative connections between said shaft and the stitch-forming mechanism, and driving means including a power-belt extending upwardly through the standard from beneath the base of the latter and operatively connected with the main-shaft.

39. A sewing machine constructed with a frame comprising a standard and a work-supporting member connected with, offset from and extending in a direction transverse to said standard, a loop-taker disposed in that portion of the work-supporting member farthest from its connection with the standard, a reciprocating needle coöperating with said loop-taker, and a support for said needle movably mounted at a point adjacent the opposite end of the work-supporting member.

40. A sewing machine constructed with a frame comprising a standard and a work-supporting member connected with, offset from and extending in a direction transverse to said standard, a loop-taker disposed in that portion of the work-supporting member farthest from its connection with the standard, a reciprocating needle coöperating with said loop-taker, a presser-foot, and supports for said needle and presser-foot movably mounted at positions adjacent the opposite end of the work-supporting member.

41. A sewing machine constructed with a frame comprising a standard, an intermediate member extending laterally therefrom and spaced above the base thereof, and a work-supporting member sustained by the intermediate member and offset from and extending in a direction transverse to said standard, a loop-taker disposed in that portion of the work-supporting member farthest from said intermediate member, a reciprocating needle coöperating with said loop-taker, a presser-foot, and supports for said needle and presser-foot movably mounted on said intermediate member.

In testimony whereof, I have signed my name to this specification, in the presence of two subscribing witnesses.

ALBERT H. DE VOE.
